DESIGN FOR A HANDLE FOR POCKET-KNIVES.

40,998.

Specification for Design.

Patented Nov. 29, 1910.

Application filed September 3, 1910. Serial No. 580,465. Term of patent 7 years.

To all whom it may concern:

Be it known that I, ROBERT C. VOM CLEFF, a citizen of the United States of America, residing at Hoboken, in the county of Hudson and State of New Jersey, have invented a new, original, and ornamental Design for a Handle for Pocket-Knives, of which the following is a specification, reference being had to the accompanying drawing, forming part thereof.

The figure is a plan view of a pocket knife with ornamented scales or handle members, showing my design.

I claim:

The ornamental design for a handle for pocket knives, as shown.

ROBERT C. VOM CLEFF.
